The ornamental design for a child safe beverage can lid, as shown and described.

DESCRIPTION

FIG. 1 is a perspective view of a child safe beverage can lid showing our new design in a first configuration;

FIG. 2 is a front elevational view thereof;

FIG. 3 is a rear elevational view thereof;

FIG. 4 is a left side view thereof;

FIG. 5 is a right side view thereof;

FIG. 6 is a top view thereof;

FIG. 7 is a bottom view thereof;

FIG. 8 is a perspective view of the child safe beverage can lid showing our new design in a second configuration;

FIG. 9 is a front elevational view thereof;

FIG. 10 is a rear elevational view thereof;

FIG. 11 is a left side view thereof;

FIG. 12 is a right side view thereof;

FIG. 13 is a top view thereof;

FIG. 14 is a bottom view thereof.

FIG. 15 is a perspective view of the child safe beverage can lid showing our new design in a third configuration;

FIG. 16 is a front elevational view thereof;

FIG. 17 is a rear elevational view thereof;

FIG. 18 is a left side view thereof;

FIG. 19 is a right side view thereof; and,

FIG. 20 is a top view thereof.

The even dashed lines depict environment and form no part of the claimed design.
